United States Patent Office

Des. 208,766
Patented Oct. 3, 1967

208,766

AIRPORT BUILDING

Samuel J. Solomon, 9101 Colesville Road, Silver Spring, Md. 20910, and John S. Samperton, Sumner, and William Procopiow, Bethesda, Md.; said Samperton and said Procopiow assignors to said Solomon

Filed Feb. 6, 1967, Ser. No. 5,709

Term of patent 14 years

(Cl. D13—1)

Fig. 2.

Fig. 3.

FIG. 1 is a top plan view of an airport building, showing our new design;

FIG. 2 is a front elevational view, looking in the direction of the arrows 2—2 in FIG. 1;

FIG. 3 is a side elevational view, looking in the direction of the arrows 3—3 in FIG. 2;

FIG. 4 is a rear elevational view, looking in the direction of the arrows 4—4 in FIG. 3; and

FIG. 5 is a side elevational view, opposite FIG. 3, looking in the direction of the arrows 5—5 in FIG. 4.

We claim:

The ornamental design for an airport building, as shown.
